UNITED STATES PATENT OFFICE.

JOHN J. R. PATRICK, OF BELLEVILLE, ILLINOIS.

METHOD OF MAKING CROWNS FOR TEETH.

SPECIFICATION forming part of Letters Patent No. 373,751, dated November 22, 1887.

Application filed April 21, 1886. Serial No. 199,640. (No model.)

To all whom it may concern:

Be it known that I, JOHN J. R. PATRICK, a citizen of the United States, resident at Belleville, in the county of St. Clair and State 5 of Illinois, have invented a certain new and useful Method of Making Crowns for Teeth; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a side elevation. Fig. 2 is a front elevation. Fig. 3 is a transverse section. Fig. 4 is a vertical section. Figs. 5, 6, 7, 8, 9, 10, 11, and 12 are detail views of various parts; and Fig. 9 is a view of the 20 male die.

The invention relates to improvements in the method of making plate-metal crowns for teeth; and it consists in the hereinafter-described successive steps by which perfect 25 crowns are obtained.

Referring to the drawings by letter, A designates the press or stamp by means of which the crowns are made, A' being the base-plate thereof, and A² the standard, in the upper end 30 of which the operating-lever is journaled.

B is the seat for the lower or female dies, secured in the base-plate, A', and provided with the upwardly-extending side flanges, B' B², between which the die-plates travel. The 35 die-plates are provided with longitudinal grooves in the side, into one of which grooves the set-screw B³ enters to hold the die in position when set.

H is the head or tool-holder moving between the walls I' I² of the press-standard and moved by the lever-handle X, which turns the cam-shaft I. The said shaft is journaled in the walls I' I² and carries between them the cam K², which engages in the transverse slot 40 H⁴, which has a central downward extension.

The wall I' is made detachable to permit the easy insertion of any one particular tool, and is held to the standard by the bolts I¹ I⁴ passing through the lugs I⁵ and entering the 45 threaded seats I⁶ in the wall I⁷. The head H has a socket into which the upper ends of the

different tools are fitted, so that said tools are interchangeable.

H³ is a set-screw passing through a tapped opening in the head H, and entering a groove 55 in the shank of the connected tool to keep the same in place.

E is the cutter-plate, by means of which and the cutter-tool P the blanks of the crowns are stamped out of the strip of plate metal. 60

F is the perforated plate by means of which the body portion of the crown is formed. The perforations Q in the plate F are of different sizes and each is rabbeted, as at Q', around its upper orifice. This perforated plate acts in 65 conjunction with the tool P', having a rounded end, to knock up the flange or body portion q² of the crown. (See Fig. 12.) The crown is then cup-shaped, having its closed end rounded. The forming-plate G is then secured 70 in the die-seat B, with one of the openings G' vertically below the tool secured to the head. The said openings are each irregular in outline, the latter corresponding with the cross-section of a particular tooth, and into said 75 openings the cup-shaped blanks are forced by a tool having a cross-section of the exact size and shape in cross-section of the tooth over which the cap or crown has to be fitted.

J is a plate provided with the recesses J', so each of which is made to fit accurately upon a certain tooth, and K is a male or outwardly-standing die corresponding to a certain recess, there being a male die for each recess. The cup-shaped crown, after its cross-section has 85 been shaped by the plate G and the corresponding male die or punch, is inserted in the proper recess J', and the corresponding die K set above it in proper relative position to the recess. A hammer, R, is then secured to the head 90 H and brought down on the die K, forming the tubercles or cusps on the metal cup-shaped crown, the latter being shaped between the recess J' and the cusped end k of the die K. The stock from which the plate metal is made 95 must not be greater in thickness than No. 29 nor less than No. 30, American standard gage.

The method thus comprises four steps: first, cutting the disk from the metal strip; second, rounding the edge or making the body-flange 100 of the disk; third, forming the flange or body to fit a tooth in cross section; and, fourth, form-

ing the cusps or tubercles on the crown. The blank is annealed after being cut from the strip and after each separate step in the method. If the body of the crown should not embrace 5 the male die close enough to be properly formed, a few taps with a light hammer will drive it down and rectify the same.

Having described my invention, I claim—

The herein-described method of making 10 metal crowns for teeth, which method consists in cutting a circular disk or blank from plate stock of a thickness equal to No. 29 or No. 30, American gage, annealing said disk, knocking

up a circumferential or body portion around 15 the edge of the blank, annealing the blank, forming the cross-section of the cup-shaped blank to fit the desired tooth, annealing the blank, forming the cusps upon the blank, so as to complete the crown, and annealing the finished crown, substantially as specified. 20

In testimony whereof I affix my signature in presence of two witnesses.

JOHN J. R. PATRICK.
